UNITED STATES PATENT OFFICE.

JOHN DESMOND, OF WILMETTE, ILLINOIS.

MEANS FOR STARTING INTERNAL-COMBUSTION ENGINES.

1,098,888.

Specification of Letters Patent.

Patented June 2, 1914.

Application filed May 3, 1913. Serial No. 765,206.

To all whom it may concern:

Be it known that I, JOHN DESMOND, a citizen of the United States, residing at Wilmette, in the county of Cook and State 5 of Illinois, have invented certain new and useful Improvements in Means for Starting Internal-Combustion Engines, of which the following is a specification.

My invention relates to improvements in 10 means for starting relatively large internal combustion power engines.

One of the objects of my present invention is to provide simplified, efficient and practical means for connecting and disconnecting 15 a smaller starting engine to a larger internal combustion power engine thereby to start the latter engine.

More specifically, my invention consists in certain details of construction and combination of parts herein shown and described 20 and particularly pointed out and defined by the appended claims.

Other and further objects of my invention will become readily apparent, to persons 25 skilled in the art, from a consideration of the following description when taken in conjunction with the drawings wherein;

Figure 1 is a longitudinal elevation of my 30 device showing it applied to an automobile engine and showing the parts of the automobile in sections. Fig. 2 is a transverse section taken on line 2—2 of Fig. 1. Fig. 3 is an enlarged transverse section of the double starting drum, taken on line 3—3 of Fig. 1 showing the ratchet and pawl connecting 35 means. Fig. 4 is an enlarged, longitudinal, central section of the same, taken on line 4—4 of Fig. 1 and on line 4—4 of Fig. 3. Fig. 5 is an end elevation of the starting 40 engine, showing the shaft of the power engine in section, taken on line 5—5 of Fig. 1. Fig. 6 is an enlarged central section of the connecting clutch, taken on line 6—6 of Fig. 1 showing the members disconnected and separated. Fig. 7 is an enlarged transverse section, 45 taken on line 7—7 of Fig. 1. Fig. 8 is a fragmental view of the clutch members, shown in Fig. 6, showing them engaged.

In all the views the same reference characters are employed to indicate similar parts.

In my copending application, Means for starting internal combustion engines, filed Jan. 3rd, 1913 and identified by Serial No. 740,052 I have shown a structure that in 55 many respects is generally similar to that of my present invention, the differences ap-

pearing in the arrangement and coöperation of the parts.

In the present exemplification 10 and 10' are the longitudinal members of the frame 60 of an automobile, upon which is mounted an internal combustion power engine 11, which is employed to propel the vehicle. A shaft 12, of said engine, is provided with a fly wheel 13 upon which is mounted an annular 65 gear 14. The annular gear may be an integral part of the fly wheel, or it may be a separable part secured thereto.

A small internal combustion engine 15, 70 that may be readily started by a foot treadle, or manual means, is arranged upon the cross bar, 16, with its base 15 inclined, being so arranged, with reference to the casing 20, as to give the engine a slight inclination. To the shaft 17, on the small engine, is secured 75 a geared pinion 18 and to the casing 20 of the small engine, is secured a stud 19, upon which the rotatable clutch members 21 and 22 are mounted. The member 22 is provided with a sleeve 23 which overlies the 80 stud 19 and provides the bearing for this member. The member 21 is provided with a perforated boss 24 which has bearing support upon the sleeve 23 and is laterally shiftable with reference to member 22. Both 85 members are freely rotatable upon the stud 19 and the member 21 may be laterally shifted into the position shown in Fig. 6 in which it is disconnected from the member 22, or it may be placed in the position shown 90 in Fig. 8 where the clutching members 21' and 22' are in engagement. A washer 25 is held in place on the stud 19 by means of a cap screw 26 threaded into the end thereof to prevent the entire displacement of the 95 member 21 from said stud. The members 21 and 22 proper are, as a matter of fact, gear wheels, as shown in Fig. 5. The member 21 is adapted for intermediate transmission, by geared relation between the pinion 18 and the geared annulus 14 of the fly wheel 13 when in proper position for this purpose, as will be hereinafter described.

The members 21' and 22' are three jawed 100 clutch members, adapted for interclutch relations, as shown in Fig. 8. It will be observed that the parts 27, of these jaws, overhang somewhat so that in order to separate them there must be first some relative rotary motion of the parts before they may be 110 separated by a relative lateral movement. The clutch members are secured to the re-

spective gear members by rivets 28, or other suitable means. The sliding member 21, of the clutch, is adapted to be laterally moved on the sleeve 23 by a forked rod 29 so that the clutch member 21' may be placed in position for driving relation with clutch member 22', or moved into the disconnected position shown in Fig. 6.

A hand lever 30, pivoted, as at 31, and having an extension 32, is connected to the forked rod 29, as at 33, and by this means, when the lever 30 is moved to a rearward position the rod 29 is moved forwardly and disengages the clutch member 21' from the clutch member 22' thus separating the members, as shown in Figs. 1 and 6. When the lever 30 is released the spring 33' being potentiated by the previous movement of the lever 30, will return the parts to their normal position, shown in Fig. 1, wherein neither of the geared members 21 or 22 are in contact with the geared rim 14 of the fly wheel.

For convenience of starting the engine 15, by foot pressure, or by hand pressure, I extend the shaft 17 of the engine 15 outwardly toward the foot board 35 and over the end 17' of the shaft 17 of the small engine, I place a double drum 36, having a smaller drum 37 and a larger drum 38. To the extended end 17' of the shaft 17, is secured a ratchet wheel 39 by means of a key 40. The drum is held in place between the ratchet wheel 39 and the nut 43. The nut is adapted to screw on the threaded end 42 of shaft 17' and to hold the washer 41 in place to prevent displacement of the drum. Secured to the drum are ratchet pawls 44 and 45 yieldingly held in contact with the teeth of the ratchet wheel 39 by means of the springs 46-46 so that when the drum 36 is rotated in one direction it will drive the shaft 17 through means of the ratchet wheel and ratchet pawl connections, and when it is rotated in the opposite direction the drum will be rotated independently of the shaft 17. Secured to the smaller drum 37 is a strap, or belt, 47 having its free end connected to a spring 48 as at 49, the other end of the spring 48 being connected to a fixed part of the vehicle, as at 50. To the larger drum 38 is secured a strap or belt 51 the free end of which is connected to a stationary portion of the vehicle as at 52. The belt 51 passes over the top of the two stationary rollers 53 and 54 that are supported on a part of the vehicle frame. In the guide 55 secured to the foot board 35 is a vertically movable press rod 56 carrying on its lower free end a roller 57. This roller, 57 is in a vertical plane midway between the rollers 53 and 54 and in a longitudinal plane, when in raised position, just slightly above the belt 51.

Now to start the small engine,—assuming that the fuel supply and ignition means

have been properly arranged—it is only necessary to depress the lever or vertically moving rod or plate 56, downwardly when the pulley or roller 57 will pass to the position shown in dotted lines in Fig. 2 thereby causing rotation of the shaft 17 of the small engine by engagement of the pawls 44 and 45 with the teeth of the ratchet wheel 39

causing the shaft 17 of the small engine to make several revolutions during each reciprocation of the vertically movable part 56.

When pressure, upon the part 56, is released the spring 48 will return it to its normal position, shown in Fig. 2, and by means of the ratchet relation between the drum 36 and the shaft 17, the drum will be freely rotated in the opposite direction to which the shaft 17 is now turning, or was turned in the initial operation of the device, so that if the small engine is not started by the first reciprocation of the vertically movable part 56

the part may again be depressed until the small starting engine has been set in motion so as to become self propelling. Now when the small engine is self propelling the lever 30 is moved to a forward position until the geared member 21 is reciprocated along the sleeve 23 so that the gear teeth thereof makes intermeshing connections with the gear teeth

on the annulus 14 of the fly wheel 13, thus bringing the geared member 21 into association with the fly wheel before the clutch members 21' and 22' are engaged, thereby assuring a proper geared relation before the clutches are associated. A further forward movement, of the lever 30, will cause engagement of the laterally shiftable clutch member 21' with the relatively rotating member 22' whereby the shaft 12 of the engine 11 will be rotated by the instrumentality just described.

If now the lever 30 be released the spring 33' will not be of sufficient power to return the clutch member 21' to the position shown in Fig. 1 because the lips 27-27 of the clutching members 21' and 22', respectively, overhang, and inasmuch as the rotation of the smaller engine tends to preserve this relation, the spring 33'' can only move the parts in a straight lateral direction, the overhanging lips of the clutch members serve to maintain the clutches in their normal position.

After the power engine 11 becomes self propelling, when the shaft has been primarily rotated in a manner described, the clutch member 21' will have been moved ahead of the clutch member 22' by the faster speed of the larger engine, and thereby the overhanging lips 27, of the respective clutch members will be moved from the same longitudinal planes and the spring 33'' will then be sufficiently powerful to move the clutch member 21' out of engagement with the clutch member 22'.

When this is done, which will follow as a natural sequence of the operation, the larger

power engine 11 will be entirely disconnected from the starting engine and the starting engine can then be stopped by shutting off the fuel supply, as usual in the operation 5 of such engines.

It will be observed, from the foregoing description, that after the starting engine has been set in motion, by the manual means shown, the geared relation between the two 10 engines is first established before the clutch is operated so that in connecting the two engines together there is no danger of stripping the gear teeth from the gear wheels it will further be observed that when the member 15 22 is being rotated by the smaller engine, the sleeve 23, upon which the member 21 is mounted will give a certain rotative movement to the member 21 by the frictional engagement of the parts so that by manipulation of the lever 30 the geared relation between the members 21 and 14 may be quickly and easily established, after which the more positive engagement of the clutch members 20 21' and 22' may be effected by further movement of the lever 30.

While I have herein disclosed a single embodiment of my invention for the purpose of a clear explanation thereof it is evident that many changes may be made in 30 the specific structure within the contemplation of the appended claims.

Having described my invention, what I claim is:

1. In a device of the character described, 35 a power engine to be started; a starting engine; connecting means for said engines, normally disconnected; means for connecting said connecting means; means, operable by the starting engine for maintaining such 40 connection while the power engine is driven thereby; an automatic means potentiated by the operation of said connecting means, for disconnecting said connecting means when the power engine becomes self propelling.
2. In a device of the character described, 45 a power engine to be started; a starting engine; a connecting, two part clutch for said engine, normally disconnected; means for engaging said clutch members; locking 50 means for said clutch members operable by the starting engine for maintaining such connection while the power engine is driven thereby; an automatic means, potentiated by

the operation of said connecting means for disconnecting said clutch members when the 55 power engine becomes self propelling.

3. In a device of the character described a power engine to be started; a starting engine; a two part clutch for connecting said engines, one part whereof is for driving as 60 sociation with the starting engine and the other part for driving association with the power engine, and means for moving one of said members into driving relation with its respective engine and subsequently into 65 driving relation with the other clutch member.

4. In a device of the character described, a power engine to be started; a gear wheel on said engine; a starting engine; a clutch 70 member rotatable by the starting engine, and a shiftable clutch member adapted and arranged to establish rotary engagement with said power engine and subsequently with said rotary clutch member. 75

5. In a device of the character described, a power engine to be started; a gear wheel on said engine; a starting engine; a clutch member rotatable by the starting engine, and a shiftable clutch member normally disengaged, adapted and arranged to first establish rotary engagement with said power engine and subsequently with said rotary clutch member and automatic means to return said shiftable clutch member to normal 80 position after said power engine becomes self propelling. 85

6. In a device of the character described, a power engine to be started; a starting engine; a clutch member, rotatable by the 90 starting engine; a clutch member for rotative engagement with said power engine; means for connecting said clutch members; means adapted and arranged to automatically separate said clutch members; and 95 means to hold said clutch members in operative engagement until the power engine clutch member is rotating at a higher speed than the starting engine clutch member.

In testimony whereof I hereunto set my 100 hand in the presence of two witnesses.

JOHN DESMOND.

In the presence of—

FORÉE BAIN,
MARY Y. ALLEN.
